UNITED STATES PATENT OFFICE.

JOSEPH J. CRIPPEN, OF DENVER, COLORADO.

DRILL OR BIT CHUCK.

SPECIFICATION forming part of Letters Patent No. 664,127, dated December 18, 1900.

Application filed August 21, 1900. Serial No. 27,596. (No model.)

To all whom it may concern:

Be it known that I, JOSEPH J. CRIPPEN, a citizen of the United States, residing at Denver, in the county of Arapahoe and State of Colorado, have invented certain new and useful Improvements in Drill or Bit Chucks; and I do declare the following to be a full, clear, and exact description of the invention, such as will enable others skilled in the art to which it appertains to make and use the same.

My invention relates to improvements in drill or bit chucks, and has for its object the production of a chuck having a simple and efficient construction and arrangement of parts whereby the jaws may be easily and speedily adjusted, combined with jaws of peculiar construction adapted to firmly and securely lock the drill or bit against longitudinal or axial movement and to receive drills or bits of different forms.

With this and other minor objects in view the invention consists of certain novel features of construction, combination, and arrangement of parts, as will be hereinafter more fully described, and particularly pointed out in the appended claims.

In the accompanying drawings, Figure 1 is a longitudinal section of a bit or drill chuck embodying my invention. Fig. 2 is a transverse section on the line 2 2 of Fig. 1. Fig. 3 is a similar view on line 3 3 of Fig. 1. Fig. 4 is a top plan view of the bushing. Fig. 5 is a side elevation of the jaws detached and arranged as in use, and Fig. 6 is a perspective view of one of the jaws.

Referring now more particularly to the drawings, wherein like reference characters designate corresponding parts throughout the several views, the numeral 1 represents the head or socket of the chuck, into which is screwed the stock, spindle, or standard carrying the chuck or the forward end of the ram when a rock-drill is employed. This socket is reduced to form an annular shoulder 2, which seats upon the outer end of an annular flange or collar 3, formed upon a bushing 4, and a tubular stem 5, which is screwed into said flange and rests upon the outer end of the bushing. The bushing in turn is threaded into the outer cylindrical chamber 6 of an adjusting sleeve or nut 7 and rests against a

shoulder 8, formed at the base of said chamber. In the body of the bushing are formed vertical grooves or slots 9, terminating in recesses 9^a, which are adapted to receive locking-lugs on the jaws, as hereinafter described. Below the shoulder 8 the sleeve 7 tapers interiorly to form a flaring chamber 10, which receives the clutch-jaws 11, which are exteriorly curved and taper longitudinally and when assembled form a clutch device of exterior frusto-conical form. The inner broad ends of the jaws bear against the lower end of the bushing and are provided with shanks 12, on which are formed lugs 13, which fit within the recesses 9^a, and vertical guide-flanges 14, which fit within the slots 9, by which means the jaws are held in position and prevented from having any but a radial movement toward and from each other and toward and from the axis of the chuck, so as to be adjusted to clamp bits and drills of different sizes. The jaws are of peculiar formation, each in addition to being tapered having a spiral twist of any desired degree—one-third, one-half, two-thirds, or a greater or less degree, as may be found most efficient or desirable. They are also provided with clamping-faces 15, disposed longitudinally and axially on their inner sides, and these faces conform to the general shape of the jaws, having a spiral twist or curvature. By this construction the gripping action of the jaws is materially enhanced, as the spiral twist imparted thereto prevents any longitudinal slipping or axial play of the bit or drill held between them in a manner readily understood. When the jaws are assembled in the chuck for use, the clamping-faces 15, while spirally disposed on the jaws, extend longitudinally in the axial line of the chuck, so as to bear throughout their entire length against the surface of the bit or drill, whereby a firm and secure clamping action is insured. The construction is also such that bits and drills of different forms in cross-section may be received and rigidly clamped.

The number of jaws employed may be varied according to the size of the chuck and the taste or fancy of the user, and other changes in the construction may be made without departing from the spirit or sacrificing any of the advantages of the invention.

Having thus fully described my invention, what is claimed as new, and desired to be secured by Letters Patent, is—

1. In a chuck, clamping-jaws having a spiral twist and registering contiguous edges.
2. In a chuck, clamping-jaws provided with bit-bearing faces having a spiral twist.
3. In a chuck, tapered clamping-jaws having longitudinal bearing-faces, the jaws and their bit-bearing faces having a spiral twist.
4. In a chuck, the combination of a socket, a bushing having a screw-threaded connection therewith and formed with a shoulder abutting against the lower end of said socket and with vertical grooves and communicat-

ing recesses, jaws provided with guide-flanges and locking-lugs to enter said grooves and recesses, and formed with tapering outer sides, and with a shoulder to engage the lower end of said bushing, and an adjusting-sleeve having a tapered base and a screw-threaded connection with the bushing, substantially as set forth. 20

In testimony whereof I have hereunto set my hand in presence of two subscribing witnesses. 25

JOSEPH J. CRIPPEN.
